UNITED STATES PATENT OFFICE.

RICHARD HENKMANN, OF BERLIN, GERMANY.

BOTTLE-STOPPER.

SPECIFICATION forming part of Letters Patent No. 398,832, dated March 5, 1889.

Application filed October 15, 1888. Serial No. 288,192. (No model.)

To all whom it may concern:

Be it known that I, RICHARD HENKMANN, a subject of the King of Prussia, in the German Empire, and a resident of the city of Berlin, 5 in the Kingdom of Prussia, Germany, have invented certain new and useful Improvements in Bottle-Stoppers, of which the following is a specification.

The principal and novel feature of this invention consists in the arrangement of an eccentric disk serving as stopping-plate, and which by means of a concentric guide either opens or shuts the mouth of the bottle.

In the accompanying drawings, Figure 1 is 15 a vertical section of the stopping apparatus fixed to the neck of the bottle when opened; Fig. 2, a top view of plate *a*, with stopping-plate *d* in place when open; Fig. 3, the same when shut; Fig. 4, the lid as seen from within.

As will be seen from the drawings, the shutting apparatus consists of a lid, *g*, Fig. 4, with pin *i*, the sieve-like openings *m*, and the flange *h*, and of a plate, *a*, with flange *b* and pin *f*. In the middle of plate *a* there is an opening, *o*. To this plate is fixed, turning around the pin *f*, an eccentric stopping-plate, *d*, with a slot, *e*, and an opening, *n*, in such a manner that when opened, Fig. 2, the opening *o* in plate *a* and the sieve-like opening *m* in lid *g* communicate with opening *n* in stopping-plate *d*. The inner side of flange *b* is provided with a worm, by which plate *a* is screwed onto box *e*, fixed on bottle-neck *l*, and likewise provided with a worm.

The apparatus is worked in the following manner: Having secured plate *a* with its flange *b* on box *e* of bottle-neck *l*, the lid *g*, with its flange *h*, is placed like a capsule on

flange *b* of plate *a*, so that its pin *i* fits into slot *e* of stopping-plate *d*, and that its flange *h* lies loosely and capable of being turned on the outside of flange *b*. To prevent the lid *g* from falling off in case the bottle is capsized or from being unintentionally taken off, there are screws *k* catching below flange *b* without 45 preventing the rotation of the lid *g*.

Fig. 1 shows the stopping apparatus on the bottle in its opened state, so that openings *o*, *n*, and *m* lie one upon another and allow liquid to be poured out.

In order to shut the bottle, the lid *g* must be turned in the direction of the arrow *B*, Fig. 2. The pin *i* in the slot *e* takes the stopping-plate *d* rotating on *f* along with it when the lid is being turned, the opening *n* of the stopping-plate *d* is placed as seen in Fig. 3, and plate *d* closely shuts opening *o*, thus producing a hermetical shutting of the bottle. By turning the lid in an opposite direction, *A*, Fig. 3, the bottle is opened by opening *n* again 60 appearing above opening *o*, Figs. 1 and 2.

I claim—

A bottle-stopper consisting of a plate, *a*, having the opening *o* and pivoted eccentrically thereon, the plate *d*, having the opening 65 *n* and the eccentric slot *e*, and the lid *g*, having the pin *i* and turning concentrically on plate *a*, as and for the purposes herein shown and set forth.

Signed at Berlin, in the Kingdom of Prus- 70 sia, this 25th day of September, A. D. 1888.

RICHARD HENKMANN.
